UNITED STATES PATENT OFFICE.

ERWIN R. JONES, OF COLUMBUS, OHIO, ASSIGNOR OF ONE-HALF TO JAMES V. OLIVER,
OF COLUMBUS, OHIO.

TWINE CUTTER.

Application filed January 11, 1922. Serial No. 528,402.

To all whom it may concern:

Be it known that ERWIN R. JONES, a citizen of the United States, residing at Columbus, in the county of Franklin and 5 State of Ohio, has invented certain new and useful Improvements in Twine Cutters, of which the following is a specification.

This invention relates to improvements in twine, string or cord cutters, and has for 10 its primary object the provision of a simple, positive and effective device for facilitating the severing at desired points of a flexible fabric cable.

Another object resides in the provision 15 of a cord severing device, which consists of a suitable base formed to include a rigid upstanding knife element protected by a soldered guard, there being a resilient pressing device situated adjacent to the sharpened edge of said element for the purpose 20 of forcing a cord into severing relationship therewith so as to insure the severing of the latter irrespective of varying diameters or tenacity of the cord.

25 Another object of the invention rests in the provision of a cord severing device which may be readily handled by the operator or maintained in a stationary position during operation and wherein the construction of the device will be such as to enable 30 the same to be safely employed without injury to the user.

For a further understanding of the invention, reference is to be had to the following description and the accompanying drawing, in which:

Figure 1 is a side elevation of the improved cord severing tool comprising the present invention.

40 Figure 2 is a vertical sectional view taken therethrough on the line 2—2 of Figure 1.

Figure 3 is a top plan view.

Referring more particularly to the details of the invention, and to the specific 45 form thereof disclosed in the accompanying drawing there is provided a base plate 1, formed to include counter sunk openings 2 adapted to receive suitable fastening elements by means of which the base may be 50 secured to any suitable stationary support. The plate 1 is provided with an axially disposed upstanding boss 3, in which is formed a threaded bore 4 adapted for the reception of the lower threaded end 5 of an upstanding post 6, the latter being provided with

an annular flange 7 limiting its threaded movement downwardly upon the boss 3.

Arranged to be removably positioned upon the post 6 and to be frictionally secured thereto is a tubular handle 8 of the tool. The upper end of this handle is threaded as at 9 to receive an integral threaded stud 10 provided upon the lower part of a knife base 11. This base is of cylindrical form, and is preferably formed in two parts, the said parts being securely held together by means of a transversely extending screw 12, which define therebetween a vertical slot 13. Arranged to be positioned within this slot and frictionally mounted in the base is the lower end of an upstanding knife element 14. This element is preferably formed from tool steel and includes a triangular blade having oppositely disposed and downwardly diverging 75 cutting edges 15, against which the cord to be severed is adapted to be pressed and thereby cut.

Surrounding the knife base 11 is a tubular guard 16, which has its lower end secured to the base 11 by means of a screw or an equivalent device 17. At this point 80 it will be observed that the guard 16 encloses the screw 12, and prevents the latter from rotating, thereby locking the two sections of the base 11 together. The upper end of the guard 16 has its opposite walls provided with registering slots 18, defining 85 therebetween horizontally curved arms 19, which are so situated as to protect the edges 15 of the knife element and prevent injury 90 to the user of the tool.

Another important feature of the invention resides in associating with each of the cutting edges of the knife element resilient 95 finger members 20. Each of these finger members are of U-shaped formation and has the lower ends thereof imbedded in the base 11. The parallel arms 21 of said members extend upwardly and in parallelism 100 with the sides of the knife element 14, and terminate in outwardly directed inclined loops 22. These loops diverge upwardly and serve in the capacity of guides for directing the cord to be severed toward the 105 edges 15 of the knife element.

In operation a flexible cable, such for example as a suitable length of cord, which is adapted to be severed, is placed against the loops 22 of the finger members and is then 110

forced downwardly until it engages with the knife edges 15. When this engagement initially occurs, the said finger members will be flexed and will exercise therefore a sufficient degree of pressure or tension upon the cord, in proportion to its thickness and the material from which it is formed to insure prompt severing thereof. If heavy twine be placed in the cutter, the pressure which 10 the members 20 exercise thereon will be correspondingly greater than that pressure which the fingers exercise upon an ordinary piece of tying cord. By the inclusion, therefore, of the finger members 20, the 15 operation of the device is rendered extremely effective and the task of severing cords of various thickness rendered simple and easy to perform, without requiring manual effort of any moment. It will be seen that 20 the device may be used either when employed in connection with the base plate 1 or when wielded by grasping the handle 8, and removing the same from the plate 1, in the manner of a knife. This tool may be 25 usefully employed in any establishment requiring devices for constantly severing cord.

What is claimed is:

1. In a cord severing device, a base, a knife element projecting from said base, a 30 guard disposed to one side of the edge of said knife element and extending substantially parallel to the latter, and a resilient finger member arranged adjacent to the cutting edge of said knife element and operating to press cord to be severed against

the sharpened edge of said knife element, a base plate, a handle having its ends detachably engaged, respectively, with the base and base plate.

2. A cord severing tool comprising a base 40 including an outwardly projecting knife element, a guard secured to said base and formed with longitudinal slots exposing the cutting edges of said knife element and a pair of resilient fingers secured to said base 45 and disposed within the confines of said guard, said fingers serving to force the material to be severed into engagement with said knife element, and out-turned guide extremities formed upon the outer ends of 50 said fingers.

3. In a cord cutting tool, a base composed of two sections, a knife element arranged to be clamped between and projected by said sections, a tubular guard for frictionally 55 engaging said sections to hold the same in clamped engagement with said knife element, and resilient fingers carried by said base and extending adjacent to the cutting edges of said knife element.

4. In a cord cutting tool comprising a base, a knife element projecting from said base, a resilient finger extending adjacent to the cutting edge of said knife element and disposed within said guard, 65 a base plate, and means for detachably connecting said base with the base plate.

In testimony whereof I affix my signature.

ERWIN R. JONES.
